UNIFORM INSIGNIA

Samuel Cohen, Seattle, Wash.

Application September 28, 1942, Serial No. 459,987

2 Claims.

(Cl. 2—246)

This invention relates to improvements in a uniform insignia for the display of insignia and more particularly to epaulet-like members commonly worn in the Navy and other uniformed services for the display of designations of rank, service branch and the like.

Heretofore it has been customary for naval officers to wear, with certain of their uniforms, stiff insignia boards which are detachably secured to the shoulder portions of their uniforms. These boards usually comprise a base member of stiff material that is covered by tightly stretched fabric. On the under side of the board is provided a mounting strap or clasps for engagement with loops or the like on the uniform. On the upper exposed face of the board, stripes of gold braid and stars, oak-leaves and other pertinent objects are secured to designate the wearer's rank and branch of service. This latter rank and service branch insignia is often, if not always, stitched to the fabric cover of the shoulder board permanently. With such a permanent arrangement, an advance in rank of an officer has always meant the acquisition of new shoulder boards even though the ones formerly applicable have not served their full usefulness. During a period of war where the size of the armed forces is being increased at a very rapid rate and the advance of commissioned officers is accelerated, the purchase of such shoulder boards, which are expensive, often works a hardship upon the men in lower ranks having generally modest incomes. No provision has been made to add or remove portions of the insignia on the shoulder boards to accommodate such changed status of the wearer.

Having in mind the limited development and defects of the prior art, it is an important object of my invention to provide insignia for shoulder boards, which insignia is easily positioned and will not readily become displaced in use.

Another object of my invention is to provide, for use with shoulder boards of the type described, insignia that is resiliently held in position on a shoulder board and will readily be movable or removable on occasion.

A still further and more specific object of the invention is the provision of shoulder boards with replaceable insignia means that is not easily displaced on the board except when desired for purposes of alteration or rearrangement.

The foregoing objects and others ancillary thereto, as will become more apparent from the following description, I prefer to accomplish as follows:

According to a preferred embodiment of my invention, I form a loop of cloth or braid material. The loop has incorporated in itself resilient means which is adapted to be tensed so that the loop may be slipped over a stiff bodied shoulder board. In the case of stripes, the braid of the loop serves

as the insignia. In the case of the loop being formed of cloth, the insignia may be formed thereon or attached thereto. Specifically, the insignia bearing loops have a resilient portion formed of elastic band that serves to contract the loop. In position, the resilient portions of the loops are disposed on the under or unexposed face of the shoulder board. Such being the case, the insignia may be added or removed or shifted as required and this may be done without recourse to sewing, gluing, or other laborious operations. In certain instances, the unexposed portions of the loops are covered by a trimming panel, preferably secured to the board to encase and finish the shoulder board.

The novel features that I consider characteristic of my invention are set forth with particularity in the appended claims. The invention itself, however, both as to its organization and method of operation, together with additional objects and advantages thereof will best be understood from the following description of specific embodiments when read in connection with the accompanying drawing, in which

25. Figure 1 is a perspective view of the upper exposed face of a shoulder board having my invention incorporated therein,

Figure 2 is a perspective view of a shoulder board from the underside with portions appearing as folded back for convenience of viewing,

30. Figure 3 is a perspective view of an insignia stripe formed according to my teaching,

Figure 4 is an elevational view of an insignia stripe of modified form that embodies my invention, and

35. Figure 5 is a cross-sectional view showing a modified manner of attaching certain of the insignia.

A shoulder board to overcome the conditions 40 and defects hereinbefore enumerated must have at least two totally distinct characteristics; it must be capable of being simply assembled with neatness by persons not having skill or mechanical ability; and it must be capable of retaining

45. the insignia properly positioned without dislodgment from ordinary use. Accordingly, a preferred embodiment of my invention, referring to Figures 1 and 2 of the drawing, is constituted by a shoulder board of stiff material on which

50. is removably mounted the desired insignia. The shoulder board, which is generally cloth covered, is designated by the numeral 10 and is shown here as a pentagon in which there are at least two right angles having an opposed pointed portion 11. It is customary in the United States Navy to cover the shoulder board with dull black cloth which is tightly stretched and glued or sewed in place.

55. 60. Insignia of rank often displayed upon such a board consists of bands or stripes 12, usually

gold or gilt braid, and service insignia as the star 13 or other suitable objects such as acorns, leaves, and the like.

In Figure 3, the band 12 is shown as having its ends folded or turned under and these ends 14, 15 are joined by a resilient tape 16. In placing such loops on the shoulder board, they are expanded against the resiliency of the tape 16 and slipped over and properly positioned laterally of the board with the resilient tape being disposed against the under face. One or more such stripes may be used and, since in color they are often gold or bright yellow, a neat contrasting appearance is created where the bands cross the exposed face and turn the edges of the board. The under turned ends 14, 15 of the bands are concealed in a manner later to be described.

It is preferable that star 13, or similar insignia, be displayed against a background that blends with the covering of the shoulder board. For that reason, the band 18, having the enlarged intermediate portion 19, is cut from cloth of a nature closely corresponding in color and texture with that of the shoulder board covering. The ends 20, 21 turn the respective edges of the board in the manner of the bands or stripes and are joined by a resilient band 22.

In mounting the desired insignia upon the board according to the requirements of the wearer the loops are stretched and slipped longitudinally over the board and then carefully positioned as to spacing and centering before the tensed resilient portions are permitted to contract. By forming the loops when relaxed of a dimension less than the lateral cross-section of the shoulder board, they will be taut and lie neatly stretched upon the face of the board.

A hinged covering panel 24 is secured to the underside of the shoulder board and, when the insignia loops are in place, this panel is swung to a position to cover the resilient portions of the loops and against the normally unexposed face of the shoulder board.

A convenient means for attaching the shoulder board is provided by attaching a strap 26 to the board. In the present instance the strap 26 is stitched to the hinged panel 24. Snap fastener elements 28, 29, one on the strap and the other on the board, permit the strap to be anchored after it has been threaded through suitable strap loops upon a uniform. When engaged, the fastener elements also retain the panel 24 tightly pressed against the underside of the shoulder board.

In Figure 4, the band 31 has the resilient strap 32 secured to the band end 33 in a more or less permanent manner, such as by stitching. The other end 34 of the band is joined to the resilient strap 32 by the cooperating elements of a snap or glove fastener 35. The mode of attachment of the band 31 is to position the band properly and then to tense the resilient strap and engage the parts of the fastener 35 whereupon the tension is released.

Thus it can be seen that the bands may be removed or shifted and that others may be added as occasion may require. In the instance of an officer being advanced from the rank of a naval lieutenant, junior grade, to a full lieutenancy, in which case he increases his paired stripes from a wide and narrow one to two wide ones, all that need be done is to remove the narrow stripe, add a second wide stripe in its place, shift the star 13, or other insignia, to provide the proper

spacing, and reattach the shoulder board. It can be readily seen that this is important from several standpoints. One advantage is that all the expensive gold braid need not be discarded and only that additionally required need be added. Another advantage is that the proper spacing of the various parts of the insignia can be maintained according to regulation merely by shifting the parts and without recourse to delicate and tedious sewing or even to cutting and reassembling.

In Figure 5 a modified means and manner of attaching the star or other similar insignia is shown. In this instance the board 40 is provided with a covering 41 and medial holes, one of which is indicated at 42. The star 43 has a threaded shank 44 which is pushed through the cloth 41 and passed through the passage 42 to properly position the device. A thumb nut 45 is threadedly engaged on the shank 44 and when tightened the star is firmly secured. By providing a series of openings 42 along the median of the board any one of several openings may be used for attaching a star in accordance with the number of bands that may be displayed, the location of the star depending upon the bands and having a regulation spacing from the one nearest the pointed end 46 of the board. This can be calculated and provided for in advance of the covering of the board and the holes used when and as required.

Although I have shown and described certain specific embodiments of my invention, I am fully aware that many modifications thereof are possible. My invention, therefore, is not to be limited except insofar as is necessitated by the prior art and by the spirit of the subjoined claims.

Having thus described my invention, I claim:

1. A shoulder board for uniforms, comprising: a stiff base member having a cloth covering, a band positioned across the viewed face of said base member and having its ends turned under the edge thereof, means operable solely in cooperation with the ends of the band for retaining the band in place, a covering panel hingedly secured along its end edge to the cloth covering of the base member and adapted to cover and conceal the ends of the band and the means cooperable therewith to trim the shoulder board and present a neat edge appearance.

2. A shoulder board for uniforms, comprising: a stiff base member forming a backing board, a cloth covering secured to said base member to cover at least the face and the edges of the base member, a female snap fastener element secured to said board and disposed on the under side thereof, an insignia band positioned across the face of said cloth covered base member and having its ends turned under the edges thereof, a resilient bridge member between said underturned ends of the band to retain the same in place, a covering panel hingedly secured to said cloth covering along its edge at the end of the base member opposite to said female snap fastener element, said covering panel having an opening in alignment with the female snap fastener element, said panel when in position lying over and concealing the band ends and the resilient bridge, and a strap hingedly secured at one end to said covering panel adjacent the hinged joinder of the same to the base member, said strap having a male snap fastener element to engage through the opening in the covering panel and into the female snap fastener element for securing the shoulder board in place on a uniform.

SAMUEL COHEN.
